UNITED STATES PATENT OFFICE

163,955

AUTOMOBILE EXHAUST PIPE EXTENSION

Byron W. McCartney, Houston, Tex.

Application October 21, 1950, Serial No. 12,648

Term of patent 14 years

(Cl. D14—6)

To all whom it may concern:

Be it known that I, Byron W. McCartney, a citizen of the United States of America, residing at Houston, Harris County, State of Texas, have invented a new, original, and ornamental Design for an Automobile Exhaust Pipe Extension, of which the following is a specification, reference being made to the accompanying drawing, forming a part thereof.

Fig. 1 is a perspective view of the top and one side of an automobile exhaust pipe extension, showing my new design, while Fig. 2 is a perspective view of the bottom and the other side thereof.

I claim:

The ornamental design for an automobile exhaust pipe extension, as shown.

BYRON W. McCARTNEY.
